DESIGN FOR A TOOL

Martin Troy McKnight, Mount Airy, N. C.

Application September 11, 1934, Serial No. 53,256

Term of patent 3½ years

To all whom it may concern:

Be it known that I, MARTIN TROY McKNIGHT, a citizen of the United States, residing at Mount Airy, in the county of Surry and State of North Carolina, have invented a new, original, and ornamental Design for a Tool, of which the following is a specification, reference being had to the

accompanying drawing, forming part thereof.

The figure is a view in perspective of a tool embodying my design.

I claim:—

The ornamental design for a tool, as shown.

MARTIN T. McKNIGHT.
